VENDING MACHINE

George P. Mergens, Hollis, N. Y., assignor to
 Arthur H. Du Grenier, Inc., a corporation of
 Massachusetts

Application April 23, 1940, Serial No. 331,145

26 Claims. (Cl. 312—95)

This invention relates to improvements in vending machines and has for an object the provision of a coin or check controlled apparatus sufficiently sturdy to protect the merchandise therein against theft, yet simple in construction, economical to manufacture, and reliable in operation.

Another object of the invention is the provision, in a vending machine, of means for individually supporting the merchandise units to be vended, without imposing the weight of any unit upon any other unit, and for successively delivering said units as the machine is operated.

A further object of the invention is the provision, in a vending machine, of a plurality of article receiving compartments or magazines arranged successively one above the other and adapted to successively discharge the article in each compartment into a common chute for delivery to the operator.

Another object of the invention is the provision, in a vending machine, of inclined supporting members, a plurality of superimposed article cells retained in position thereon by means which, when operated, successively releases the articles from said cells and permits the released articles under the urge of gravity, to enter a delivery chute.

Another object of the invention is the provision, in a vending machine, of a plurality of magazines, each having article releasing means, and an actuator common to all of said releasing means, whereby the operator may selectively actuate the article releasing means of any desired magazine.

A further object of the invention is the provision, in vending apparatus, of a plurality of magazines, each having an article releasing means associated therewith; each releasing means adapted to be advanced in steps, whereby the articles in said magazines are successively released as the apparatus is operated.

Yet another object of the invention is the provision, in vending apparatus, of a plurality of inclined supports, and article cells carried on said supports; each cell or block containing a plurality of articles, each separated from the other by a locked gate. These gates normally depend in vertical positions and are adapted to be successively released and swung into position for releasing the articles angularly.

Other objects and advantages of the invention will be apparent to those skilled in the art.

In the accompanying drawings, which are merely given as an example of one form of apparatus embodying the invention:

Figure 1 is a sectional right side elevation of the apparatus illustrating the invention;

Figure 2 is a left side elevation of the apparatus in Figure 1 with portions broken away and certain parts omitted, for the sake of clarity;

Figure 3 is a plan view of the apparatus with portions shown in section;

Figure 4 is an enlarged detail sketch of the gate mechanism with the actuating pawl for releasing the gate shown in the position for actuating the lowest gate;

Figure 5 is a view of the gate mechanism with the parts in their advanced positions;

Figure 6 is an elevation similar to Figure 4 showing how the gate is reset;

Figure 7 is a similar elevation with the parts in other positions;

Figure 8 is an enlarged section taken along the line 8—8 of Figure 4;

Figure 9 is an enlarged section taken along the line 9—9 of Figure 3;

Figure 10 is an enlarged section taken along the line 10—10 of Figure 3;

Figure 11 is an enlarged section taken along the line 11—11 of Figure 3;

Figure 12 is a detail, partly in section of a modified form of mechanism for resetting the gate releasing means;

Figure 13 is a detail, partly in section, of the modified mechanism shown in Figure 12 with some of the parts in other positions; and

Figure 14 is a detail, partly in section, taken along the line 14—14 of Figure 3.

A framework generally designated by the numeral 10 and carrying the various parts and mechanisms is housed in a casing 11, and may be bodily removed therefrom. A plurality of supporting members 12 are secured to the vertical front and rear members 13 and 14 of the framework 10 in parallel spaced relation to each other. The members 12 are arranged one above the other and slant downwardly towards the rear (Figure 2). Each member 12 has a vertical wall portion 15 formed with an inwardly directed portion 16 along the upper edge thereof having downwardly extending lugs 17 spaced apart from the wall portion 15 as shown in detail in Figure 8.

Members 13 having transversely extending magazine forming wall portions 19, 19a are secured at one side by vertical flanges 20 to the lugs 17. The magazine walls 19, 19a are arranged in vertically spaced parallel relation and extend downwardly toward the rear at an angle steeper than the angle of repose to allow articles thereon, when released, to readily slide therefrom

for delivery to the operator. The several walls 19, 19a provide therebetween a vertical series of inclined magazines 21, in which the lower wall portions 19 form the floors or supports upon which the merchandise units to be dispensed are retained. The walls 19, 19a are supported at their upper ends by a vertical frame member 22.

The front wall of the casing 11 has windows 11a formed therein in alignment with the several magazines 21 so that the uppermost articles therein (which are the final ones to be dispensed) are exposed to view.

Division of each magazine into a plurality of cells

The merchandise units to be dispensed are retained within each magazine 21 upon the inclined walls 19 thereof in spaced successive positions by a series of gates 23 pivoted at their upper edges 24 to the upper wall 19, 19a of the magazine. The gates 23 are normally under the urge of spring means 24 to swing upwardly in a clockwise direction, as shown in Figures 2 and 5 to release the articles. However the gates are retained and locked in vertical positions by members 25 retained in slidable engagement with the corresponding member 12 by the pin and slot connections 26. Thus it will be seen that the magazines 21 are each divided into a plurality of merchandise or article cells by said gates, and each time the machine is operated a gate is opened and only one article from a magazine is released; leaving all of the other articles in the other cells in said magazine and the articles in the cells in the other magazines undisturbed. The member 25 forms a part of an actuating device 27 which is advanced in steps for successively releasing or unlocking the gates 23 beginning with the lowermost one at the rear for permitting the article retained thereby to slide into the chute 28, which is common to the several compartments 21, for the delivery of articles to the operator.

The cell forming gates 23 are retained locked in vertically depending positions against the urge of the spring means 24 by the engagement of the rear fingers 29 on the gates with the underside of an overhanging flange 30 extending longitudinally on the slide 25 from the upper edge thereof. The flange 30 has equally spaced openings 31 formed therein which in the forward or normal position of the slide 25 are positioned at progressively increasing distances from the points of engagement of the upper edges 32 of the laterally directed angular portions 29a of the fingers 29 with the flange 30.

The actuating device 27 may have a ratchet mechanism including a ratchet member 33 secured to the slide 25 in spaced relation thereto by the pins 34 with supporting member 12 therebetween. A recess 35 (Figure 7) provides clearance for the pins 34 when the members are actuated. A number of teeth 36 (corresponding with the number of gates to be actuated or released) is formed in the upper surface of the ratchet member 33. See Figure 1.

Successive release of the cell gates

Each member is actuated by the successive engagement of a pawl 37 with the teeth 36. The pawl 37 is pivotally connected at 38 to one arm of a bell-crank 39 pivotally connected to the member 12 by pivot stud 40. The other arm of the bell-crank carries a stud 41 adapted to be engaged in cooperative relationship by a common actuator means 42 as will presently be de-

scribed. A spring 43 has one end connected to the pawl 37 and the other end connected to the bell crank 39 to normally urge the pawl 37 in a clockwise direction thereby maintaining it disengaged from the teeth 36 and to maintain the lever 39 in engagement with a stop 44 carried on the member 12. The pawl 37 in the disengaged position rests upon the pin 45. A camming portion 46 formed on the pawl cooperates with said pin 45 for effectively guiding the end 47 of the pawl into engagement with successive teeth 36 as the pawl is successively actuated.

The upper end of the member 33 has an elevated portion 48, the upper surface of which forms the ledge 49 which supports the end 47 of the pawl 37 when it returns after the actuation of the member 33 as shown in the upper portion of Figure 1. As the pawl 37 is returning the camming surface 50 engages the incline 51 between the surface 49 and the teeth 36 and is guided thereover and onto the ledge surface 49 disengaged from the pin 45.

When the pawl 37 is at rest upon the ledge 49 cooperating with a stop 52 disposed in the path thereof it prevents full movement of the actuator 42 if the latter is connected to the pawl 27 of an empty or exhausted magazine 21. This prevents a coin or coins lodged in the coin controlled mechanism 53 from being accepted. The stop 52 may be a member pivotally supported at 54 on the member 12 adjacent to the member 33, and has its lower surface overlying and normally clearing the teeth 36. The forward end of the member 52 has a recess 55 formed therein to provide clearance for the pawl 37 as the latter (when actuated successively) moves member 33 in steps.

A relatively light spring 56 may be employed to augment the force of gravity in maintaining the stop member 52 in engagement with the ratchet member 33. The stop member 52 is therefore free to yield when engaged by the pawl 37 as it is reciprocated to advance the ratchet member 33 and will therefore not interfere with the operation of the pawl while the latter is disposed in position to act as a stop if an attempt be made to advance the pawl when the associated compartment becomes exhausted after the member 33 attains its rearmost position.

A series of recesses 57 is formed on the upper edge of the lower end of the member 33. A pivoted dog 58 has a nose 59 retained in engagement with one of the recesses 57 under the urge of a spring 60 for centering and holding the member 33 in the successive positions effected by the action of the pawl 37 against the teeth 36.

Method of supporting the actuator device

The actuator device 42 includes a portion 61 reciprocally movable on the vertical web 62 of a member 79 of L cross section secured to the vertical frame member 13, as may be seen in Figures 1 and 3. The web 62 forms a guide rail for the portion 61, while the latter also includes an intermediate portion 63 engaging the rear face of the web 62. A flange strip 64 which is a continuation of the portion 63, extends rearwardly to a point adjacent to the bell-crank 39. The opposite face of the web 62 is engaged by a strip 65 which is a continuation of the portion 61. The member 61 carries a pin 66a which extends through a slot 66 formed in the web 62, and which not only retains 61, 63, 65 in engagement with the web 62, but also defines the limits of the movement thereof.

Selectively connecting actuator with ratchet mechanisms of the magazines

The actuator device may be selectively connected in operative relation to the ratchet mechanisms 27 of any of the magazines 21 by means of latches 67 pivotally carried by the flange strip 64 contiguous to the bell-cranks 39, there being one latch for each bell-crank. The latches 67 are supported on pivots 68 carried by the flange strip 64 and normally hang downwardly from said pivots in the positions shown in Figure 1. Hooks 69 at the lower ends of the latches are thereby positioned to engage the corresponding studs 41 of the levers 39 when any one of said latches is swung rearwardly as shown in dot-dash lines in the third group down in Figure 1.

A plurality of plungers 70 have their ends extending through the front wall of the casing 11, each plunger is preferably positioned in line with the magazine it controls, so that when it is desired to obtain an article from a given compartment the operator can see which selector to operate.

The plungers 70 form a free working fit with holes formed in the flange or strip 13a and at the rear thereof are supported by the fixed guide member 62, provision being made to allow reciprocation of the actuator device 42 relative to said plungers in either of the positions thereof. Each plunger 70 carries a pin or lug 71 co-acting with the corresponding latch 67. Each latch has formed therein a V shaped opening 75, the widest portion of the V being in the upper portions near the pivots 68, and the pins normally extend into the V shaped openings at said widest portion, thereby permitting the latches to reciprocate relative to the plungers 70 in both the normal and projected positions of said latches, as the actuator device is moved. When any plunger 70 is depressed the corresponding latch 67 is swung rearwardly, as shown in dot-dash lines in Figure 1, to engage the stud 41 on the lever 39. The pin 71 of the depressed plunger by this action engages the right edge 73 of the V opening in the latch 67 to maintain such engagement during reciprocation of the actuator device 42. The pins 71 of the other plungers 70 co-act with the left edges 74 of the remaining latches 67 during the said reciprocation and to retain said last latches in inoperative positions and prevent them from being accidentally projected.

The plungers 70 carry with rearwardly extending nose portions 76 the angular faces of which may cooperate with the beveled ends 77 and 77a of the blocks 78, 78a which are retained in sliding engagement with member 79 by the guide clips 80. The lowermost block 78a is positively secured to the flange 79 and forms an abutment for the block 78 adjacent thereto. The beveled ends of the blocks 78, 78a terminate in horizontal surfaces 81 which on adjacent ends of said blocks are adapted to normally abut each other when the plungers are in projected positions. The bevels on the ends of the blocks are at approximately 45° angles with respect to the axes of the blocks, so that the ends 77 and 77a of adjacent members 78, 78a form a recess 82 therebetween of substantially ninety degrees. The angular edges 83 of each of the cooperating nose portions 76 are formed on corresponding faces to provide a right angular nose having the edges 83 thereof disposed in parallel relation to and adapted to cooperate with the adjacent faces 77 and 77a. The upper edges 83 as seen in Figures 1 and 14,

normally engage the adjacent edges 77 of the block 78 in camming relation and the lower edges 83 are in spaced relation to the edges 77a. Each nose 76 is of reduced area compared to the area of the corresponding axis of the corresponding recess 82. Upon actuation of any plunger 70, the blocks 78 above said plunger are moved upwardly to effect the displacement of a pivoted latch 84 normally disposed in the path of the actuator device 42 to prevent its actuation when none of the plungers 70 is depressed. The latch 84 also limits the upward movement of the blocks 78.

When any plunger 70 is depressed, the adjacent edges 77 and 83 cooperate to exert a camming action which elevates those blocks 78 above the plunger depressed, and cause the corresponding edges 77a thereof to engage the lower edges 83 of the noses 76 of such upper members 78. The nose portion 76 on the depressed plunger 70 enters its corresponding recess 82 to engage both edges 77 and 77a of the adjacent blocks 78, 78a. The clearance provided between the successive members 78, 78a is sufficient to allow the depression of any plunger into position as above described before such clearance is taken up by the wedging action of the depressed nose 76. In the construction as above described if a plunger 70 above the one depressed is also depressed, the block 78 engaging the upper nose edge of the second depressed plunger will be forced downwardly to exert a camming action on the plunger first depressed and force the same into projected position.

If a plunger 70 below the depressed plunger also be depressed, the member 78 engaging the lower nose edge 83 of the plunger first depressed will be forced upwardly to exert a camming action on said first plunger and likewise force the same into projected action.

Each plunger 70 has depressions 85 and 86. A spring detent 87 carried on the flange 13a cooperates with their depressions to respectively define the outermost and innermost positions of the plunger and to retain the same in either position, one detent 87 being provided for each plunger.

Each plunger 70 has formed therein slots 88 and 89 cooperating with the edge 90 of the forward flange 13 to prevent actuation of the plungers when the actuator device 42 is being actuated. The edge 90 has semi-circular recesses 91 formed therein and normally registering with the plungers 70 to allow the depression of any one thereof. When the actuator device is moved, the edge 90 thereof enters the slots 88 of the plungers which have not been depressed, and enters the slot 89 of the depressed plunger to prevent the actuation thereof.

The release of the common actuator device by coins

The common actuator device 42 is released and operated by the coin controlled mechanism 53 mounted at one side of the machine upon a panel 92. The mechanism 53 includes a support 93 upon which a coin carrier 94 slides. The carrier 94 has a coin pocket 95 into which a coin is deposited through chute 96. The slide carrier is operated by a plunger 97 also extending through the front wall of the casing 11. A detent 98 is pivoted at 99 to the panel 92 and extends rearwardly above the carrier 94. A projection 100 on the detent is normally held in the path of a shoulder 102 on the carrier 94 by the spring 101, to limit the movement of the latter when the

plunger 97 is pulled out without a coin in the carrier.

When a coin is deposited in the pocket 95, the forward movement of the slide 94 when the manual member 97 is pulled out causes the coin to exert a camming action against the nose 103 of the detent 93, raising the same thereby moving the projector 100 out of the path of the shoulder 102, and allowing the carrier 94 to move forward and the actuating device 42 to operate. As the carrier moves forward the coin is also carried forward and drops through the slot 104 to be retained.

A link 105 is pivotally connected at one end 105a to a lug 106 on the actuator device 42. The other end 105b of link 105 is pivotally connected to the coin carrier 94. The plate 92 has a slot 92a formed therein in which the pivot 105b rides.

By pushing the plunger 97 inwardly, any coin inserted may be returned before the mechanism is actuated. When the plunger 97 is pushed in, the coin is moved rearwardly until it reaches the slot 107, where it falls out into the delivery chamber at the bottom of the machine and may be recovered by the operator.

An arm 108 pivoted on the panel 92 at 120 carries on its lower end a roller finger 108a extending through a slot 108b to engage the coin carrier 94. The forward movement of the arm 108 is limited by engagement of the roller with the forward edge of the slot 108b. A spring 109 has one end connected to the link 105 and the other end connected to the swinging arm 108. When the plunger 97 is pulled out to actuate the mechanism, the link 105 is moved and the spring 109 is tensioned due to the fact that arm 108 is then stationary. On the other hand when the plunger 97 is pushed in to return the coin, the arm 108 is moved rearwardly and the tension 109 is tensioned due to the fact that the link 105 is then stationary, and the pivot 105b is free to ride in a slot 92a provided in coin carrier 94. When the plunger 97 is released after being actuated in either direction the same spring 109 causes the plunger to return to its normal intermediate position.

General description

A block 110 secured to the support 93 has serrations 121 formed along its top edge. A pawl 122 is carried on a pivot 123 secured to the coin carrier 95 and has its engaging end extending downwardly to engage the serrations 121 as the carriers are moved to the left (Figure 1). A spring 124 is secured to an ear on the pawl 122 and to the carrier 95 so as to normally maintain the pawl vertically.

The ratchet mechanism 27 for successively releasing each series of gates or partitions 23 is automatically reset or returned step-by-step to normal or starting position by resetting means 111 actuated by the several gates when each is manually returned into vertical or article retaining position, preferably at the time that the machine is reloaded with merchandise. For this purpose, the slide member 25 carries at its lower edge a series of upwardly projecting ears 112 disposed in the return paths of the lower edges 32a of the angularly related portions 29a of the fingers 29 secured to the gates 23 (Figures 6 and 7). These ears are successively arranged slightly in advance of the axes of the openings 31. When any gate 23 is released by actuation of step-by-step actuating device 27 the angular portion 29

thereof moving along the flange 30 encounters and swings into the contiguous opening 31. When any such gate 23 is thereafter manually returned to article retaining position the lower end 32a of the portions 29a engages the projection 112 to move the step actuating device 27 together with the slide 25 in the resetting direction one step as shown in Figures 6 and 7, the extent of the return movement being determined or limited by engagement of the shank portion 113 of the finger 29 with a stop 114 formed in the upper edges of the flanges 30. When the shank 113 engages the stop 114 further return movement of the parts is prevented, and upon release of the gate 23 actuated the upped edge 32 moving slightly in the reverse direction engages the flange stop 30 for retaining the gate locked in vertical or article retaining position. In like manner, two or more of the gates may be actuated to return the step actuating device 27 through a corresponding number of steps to its initial position.

A modification of the resetting means 111 is shown in Figures 12 and 13 wherein the stop 114a forms an integral angular portion of the finger 29 which also has the angularly related portion 29a adapted, as above described, to engage the flange stop 30 for retaining the gate 23 locked in vertical position and, upon actuation of the step actuating device 27, to release the gate by swinging into the opening 31. The portions 29a also serving to engage the projection 112a when the gate is swung down for returning the slide 25 one step. The stop 114a is so disposed upon the finger 29 in coordinated relation to the portion 29a that, when the extent of return movement of the slide 25, corresponding to one step, is effected the stop 114a enters the opening 31 and engages the flange edge 30 at the opening 31 to prevent further movement.

Operation of the machine

In operating the machine a selection can be made either before or after the coin is inserted, by depressing any plunger 70 desired. The corresponding latch 67 is thereby swung into engagement with the stud 41 to operatively connect the common actuating device 42 with the step-by-step actuating device 27 of the magazine selected. At the same time the latch 84, which normally serves as a stop in the path of movement of the sliding actuating device 42 to prevent operation thereof, is swung by the blocks 78 out of engagement with the device 42 to allow the actuation thereof. When none of the plungers 70 is depressed the latch 84 prevents actuation of the device 42 and coin mechanism 53, whether the proper coin has been inserted into said mechanism or not. This prevents the operation of the coin mechanism 53 resulting in the acceptance of the coin by the machine without delivery of goods to the operator, and indicates to the operator that a selection must be made before the machine will operate. When one plunger 70 is depressed, it is impossible to depress a second plunger without causing the return of the first plunger to projected position. In the presence of the proper coin and after a selection has been made, the plunger 97 is pulled out to cause the coin to disengage the detent 98 and allow actuation of the actuating device 42, all of the plungers 70 becoming automatically locked thereby.

The movement of the actuating device 42 causes the projected latch 67 carried thereby to engage the stud 41 and cause the lever 39 to swing and advance the pawl 37 into engagement

with one of the teeth 36, thus causing the member 25 to advance one step. Upon successive actuations of the device 27, the gates 23, beginning with the lower one, are successively released to effect the delivery of the articles from the cells. After gate 23 of the last cell of any magazine 21 has been actuated, the actuation of the device 42 when connected to the step actuating device 27 of such compartment is prevented by engagement of the pawl 37 with the stop 52. This prevents actuation of the coin mechanism 53 which would result in the acceptance of the coin without the delivery of merchandise. The windows 11a enable one to notice whether or not any magazine 21 is empty. If, after inserting a coin, the operator changes his mind the plunger 97 is pushed inwardly from its normal position. The gates 23 of each cell are relocked in article retaining position by manually swinging the same downwardly. The gates 23 cooperate with the slide 25 to cause each step actuating device 27 to be reset or returned step-by-step to its initial position.

From the above description it will be seen that I have provided a machine with a plurality of inclined partitions forming magazines. In order to provide a machine with a large capacity, I divide each magazine up into a plurality of cells, which are formed between a series of gates mounted in each magazine. The releasing means for releasing the gates is progressive. In other words, when the magazine is full, the first time the releasing means is actuated the first gate in the series is released thereby permitting the article in the first cell to pass out of the magazine without disturbing the articles in the other cells in the magazine. The second time the releasing means is actuated, the second gate in the series is released, permitting the article in the second cell to pass out of the magazine—and so forth until the last gate is actuated to release the article in the last cell whereupon the magazine is empty. The last article is the one which the public sees through the window, so that when it passes out of the magazine, it will be readily noted that the magazine is empty and the customer will select some other magazine.

In respect to the actuator, it will be understood that my actuator device spans all of the magazines (which are arranged in a vertical column) and moves a short distance along a well defined path defined by the pin 66 and slot 66a. The actuator has as many engaging members 67 as there are magazines, each of which is controlled by a push button 10. There is a push button alongside of or adjacent to the window of each magazine. The actuator device may be released by any desired type of coin mechanism.

By the above arrangement is provided a vending machine of large capacity, having simple and fool proof mechanism and having controls so positioned that the operation of the machine is immediately obvious to the public.

Although I have herein illustrated and described one embodiment of the invention, by way of example, it must be understood that many changes made in the embodiment shown without departing from the spirit of the invention as set forth in the following claims.

I claim:

1. In vending apparatus, a plurality of inclined magazines arranged in a vertical column, a series of gates in each magazine dividing the same into a plurality of individual cells for containing merchandise units, said gates being in-

dividually locked, progressive releasing mechanism for releasing one of said gates each time said mechanism is actuated, thereby permitting the merchandise unit in one cell in one of said magazines to discharge by gravity without disturbing the other merchandise units in said last mentioned magazine, and means for actuating said releasing mechanism.

2. In vending apparatus, a plurality of inclined magazines arranged in a vertical column, a series of gates in each magazine dividing the same into a plurality of individual cells for containing articles of merchandise, said gates being individually and successively locked as the cells are loaded with said articles, progressive releasing means adapted each time the same is actuated to release one of said gates, thereby permitting only the article in the cell bounded by the released gate to discharge by gravity, and means for actuating said releasing means.

3. In vending apparatus, a plurality of inclined magazines arranged in a vertical column, a series of gates in each magazine dividing the same into a plurality of individual cells for containing articles of merchandise, said gates being individually and successively locked as the cells are loaded with said articles, progressive releasing means adapted each time the same is actuated to release one of said gates, thereby permitting only the article in the cell bounded by the released gate to discharge by gravity, means for selecting the releasing means associated with any one of said magazines for actuation, and means for actuating the selected releasing means.

4. In vending apparatus, a casing, a plurality of inclined magazines arranged in a vertical column therein, mechanism for releasing articles from any of said magazines, an actuator device movable in said casing along a defined path in said apparatus and including a plurality of actuating members common with said mechanism associated with said magazines, selective means for operatively connecting any one of said actuating members with the releasing mechanism with which it is common, and means for controlling the movement of said actuator device along said defined path.

5. Apparatus according to claim 4 in which said inclined magazines each include means for retaining therein a plurality of articles, and in which said mechanism for retaining articles from the magazines operates in steps and effects the release of only a single article from a selected magazine for each operation.

6. In vending apparatus, a plurality of inclined magazines each including means for releasably retaining a number of articles or packages therein in series relation to be successively dispensed, means for controlling each of said retaining means to effect the release of the articles successively upon repeated actuations of said controlling means, an actuating device common to all of said several controlling means, and means selectively operable for operatively connecting said actuating device to any of said means for controlling as desired.

7. In vending apparatus, a plurality of inclined magazines, a plurality of spaced article retaining members hingedly retained in each magazine, said members being individually locked, slidably releasing means in each magazine and operable in steps for releasing said members and effecting successively the release of articles therefrom, actuating means common to all said releasing means, and means for selectively

connecting any of said releasing means in cooperative relation with said actuating means.

8. In vending apparatus, a plurality of inclined magazines, a plurality of spaced article retaining members hingedly retained in each magazine, said members being individually locked, slidable releasing means in each magazine and operable in steps for releasing said members and effecting successively the release of articles therefrom, said releasing means each including an engageable member and said last members being in alignment with each other, actuating means commonly adjacent to all said engageable members, and means controlled by an operator for selectively connecting any one of said engageable members in operative relation with said actuating means.

9. Vending apparatus, including in combination a plurality of inclined magazines arranged in a vertical column and each having a floor, means for retaining a number of articles in series relation upon each of said floors, several means for successively actuating said last means to successively release said articles singly and allow delivery thereof, an actuator device including actuating members common to said several means, selective means for operatively connecting one of said actuating members with any one of said several means, and means for moving said actuator device.

10. Vending apparatus, including in combination, a plurality of superimposed magazines including downwardly inclined supports, a series of gates in each magazine for releasably retaining articles or packages thereon on each support in series relation, means for individually and successively releasing the gates of each series to release the articles to be dispensed, an actuating device common to said last means, and means selectable by an operator for cooperatively associating said actuating device operative with any of said means for releasing said gates.

11. In vending apparatus, a plurality of magazines each having means for dispensing articles or packages therefrom, an actuating device including actuating members adjacent to said several dispensing means, selective means for operatively connecting any of said actuating members to its adjacent dispensing means, means under control of said selective means for preventing the operation of said actuating device until a selection is made, and means associated with each of said dispensing means, and rendered effective when an associated magazine becomes exhausted, to prevent operation of said actuating device as long as the latter remains in operative relation to the dispensing means of said exhausted magazine and until a new selection is made.

12. Vending apparatus according to claim 8 in which said means for selectively connecting any of said engageable members is comprised of a plurality of individual members, each of which is adapted to connect a different engageable member to said actuating means, and in which disconnecting means is provided for disconnecting a previously connected engageable member from said actuating means as a succeeding engageable member is connected thereto.

13. Vending apparatus according to claim 15, in which said means for advancing said movable holding means in steps includes ratchet means for defining said steps.

14. In vending apparatus, a magazine, a plurality of depending gates therein, each gate being pivoted at the top thereof, a slidable member

spanning all said gates and having a series of differentially spaced apertures formed therein, an engaging member on each gate normally contacting said slidable member in the solid portions between said apertures, and means for engaging and sliding said member along in steps to successively cause the engaging members on said gates to ride off said solid portions and into said apertures, thereby successively releasing said gates.

15. In vending apparatus, an inclined magazine having a floor, a series of gates above said floor dividing said magazine into a plurality of cells for containing merchandise, movable means for holding said gates in merchandise retaining positions, means for advancing said movable holding means in steps, thereby successively releasing said gates, and means on said movable holding means disposed in the paths of said gates to be engaged thereby when said gates are manually set to operative positions for imparting a step-by-step resetting movement to said movable holding means.

16. In vending apparatus, a plurality of magazines having inclined floors and arranged in a vertical column, a series of pivoted gates in each magazine forming cells for retaining articles to be vended therein whereby each article is partly supported by a gate and partly supported by the floor of its magazine, means for holding said gates in article retaining positions, means for releasing said gates successively as said holding means is moved, means including pawls and ratchets for advancing said holding means, pivoted members connected to said pawls for actuating the same to move the associated ratchet and holding means thereof, an actuating device, latches carried thereby, members associated with said latches for selectively swinging any one of the latches into engagement with a corresponding pivoted member, and thereby operatively connecting said actuating device to the pawl selected, and means to reciprocate said actuating device.

17. In vending apparatus, a plurality of magazines for merchandise, each having its own individual dispensing mechanism and a selective control for said mechanisms including a plurality of aligned members having their ends beveled, said members being capable of limited movement or end play relative to each other, the ends of some of said members being adjacent to and adapted to engage each other, selector members extending between the adjacent ends of others of said aligned members, and triangular nose pieces on said selector members adapted to engage the beveled ends of the aligned members and cam the latter apart thereby taking up the play therebetween when any one of said selector members is actuated, the relation of the angular surfaces on said nose pieces and that of the cooperating beveled ends of said aligned members being such that they form camming surfaces adapted to effect the return of one selector member when another selector member is actuated.

18. In a vending machine, in combination, a plurality of merchandise magazines arranged in a series, a plurality of depending gates in each magazine, each gate being pivoted at the top thereof and carrying an engaging member, a latching member in each magazine spanning all the gates therein in contact with the engaging members thereon and normally locking said gates against movement, a series of differentially spaced apertures formed in each of said latching members between the points of contact with said

engaging members, and means for moving any of said latching members along on its column to successively cause the engaging members on said gates to ride off the solid portions of said latching member and into said apertures, thereby successively releasing said gates.

19. Vending apparatus according to claim 18, in which said magazines are inclined to the horizontal and are disposed in a vertical column.

20. In a dispensing apparatus, a plurality of inclined magazines arranged in a vertical column, a series of gates in each magazine mounted for movement to and from positions dividing the magazine into a plurality of individual cells for retaining articles of merchandise and positions for releasing said articles, separate movable locking means operatively associated with each magazine adapted in one position to retain all of said gates in their article retaining positions and adapted by movement in one direction to successive predetermined positions to release said gates successively and by movement in the opposite direction, through said positions to permit said gates to be returned successively to their article retaining positions and maintained therein.

21. In a dispensing apparatus, a plurality of inclined magazines arranged in a vertical column, a series of gates in each magazine mounted for movement to and from positions dividing the magazine into a plurality of individual cells for retaining articles of merchandise and positions for releasing said article, separate movable locking means operatively associated with each magazine adapted in one position to retain all of said gates in their article retaining positions and adapted by movement in one direction to successive predetermined positions to release said gates successively and by movement in the opposite direction through said positions to permit said gates to be returned successively to their article retaining positions and maintained therein in the order in which they were released, separate releasing means associated with each of said locking means and adapted to be actuated to move the same in said direction step by step to said successive positions, and means for separately actuating said releasing means.

22. In a dispensing apparatus, a plurality of inclined magazines arranged in a vertical column, a series of gates in each magazine mounted for movement to and from positions dividing the magazine into a plurality of individual cells for retaining articles of merchandise and positions for releasing said articles, separate movable locking means operatively associated with each magazine adapted in one position to retain all of said gates in their article retaining positions and adapted by movement in one direction to successive predetermined positions to release said gates successively and by movement in the opposite direction through said positions to permit said gates to be returned successively to their article retaining positions and maintained therein, separate releasing means associated with each of said locking means and adapted to be actuated to move said locking means in said one direction step by step to said successive positions, a movable member, a separate actuator adjustably mounted on said member adjacent each of said releasing means for movement to and from a position for operative association with said releasing means, a separate selector associated with each actuator and movable to adjust the position of the latter, and means for moving said member to actuate one of said releasing means.

23. In a dispensing apparatus, a plurality of inclined magazines arranged in a vertical column, a series of gates in each magazine mounted for movement to and from positions dividing the magazine into a plurality of individual cells for retaining articles of merchandise and positions for releasing said articles, separate movable locking means operatively associated with each magazine adapted in one position to retain all of said gates in their article retaining positions and adapted by movement in one direction to successive predetermined positions to release said gates successively and by movement in the opposite direction through said positions to permit said gates to be returned successively to their article retaining positions and maintained therein, separate releasing means associated with each of said locking means and adapted to be actuated to move said locking means in said one direction step by step to said successive positions, a movable member, a separate actuator adjustably mounted on said member adjacent each of said releasing means for movement to and from a position for operative association with said releasing means, a separate selector associated with each actuator and movable to adjust the position of the latter, and means for moving said member to actuate one of said releasing means, and means for locking said moving means.

24. In a dispensing apparatus, a plurality of inclined magazines arranged in a vertical column, a series of gates in each magazine mounted for movement to and from positions dividing the magazine into a plurality of individual cells for retaining articles of merchandise and positions for releasing said articles, separate movable locking means operatively associated with each magazine adapted in one position to retain all of said gates in their article retaining positions and adapted by movement in one direction to successive predetermined positions to release said gates successively and by movement in the opposite direction through said positions to permit said gates to be returned successively to their article retaining positions and maintained therein, separate releasing means associated with each of said locking means and adapted to be actuated to move said locking means in said one direction step by step to said successive positions, a movable member, a separate actuator adjustably mounted on said member adjacent each of said releasing means for movement to and from a position for operative association with said releasing means, a separate selector associated with each actuator and movable to adjust the position of the latter, and means for moving said member to actuate one of said releasing means, means for locking said movable member, and mechanism adapted to be actuated by any selector, when moved to adjust its associated actuator to its operative position, to unlock said movable member.

25. In a dispensing apparatus, a plurality of inclined magazines arranged in a vertical column, a series of gates in each magazine mounted for movement to and from positions dividing the magazine into a plurality of individual cells for retaining articles of merchandise and positions for releasing said articles, separate movable locking means operatively associated with each magazine adapted in one position to retain all of said gates in their article retaining positions and adapted by movement in one direction to successive predetermined positions to release said gates successively and by movement in the op-

posite direction through said positions to permit said gates to be returned successively to their article retaining positions and maintained therein, separate releasing means associated with each of said locking means and adapted to be actuated to move said locking means in said one direction step by step to said successive positions, a movable member, a separate actuator adjustably mounted on said member adjacent each of said releasing means for movement to and from a position for operative association with said releasing means, a separate selector associated with each actuator and movable to adjust the position of the latter, and means for moving said member to actuate one of said releasing means, and mechanism adapted to be actuated by any selector, when moved to adjust its associated actuator to its operative position, to move any other selector and dislodge its associated actuator from its operative position.

26. In a dispensing apparatus, a plurality of inclined magazines arranged in a vertical column, a series of gates in each magazine mounted for movement to and from positions dividing the magazine into a plurality of individual cells for retaining articles of merchandise and positions for releasing said articles, separate movable locking means operatively associated with each magazine adapted in one position to retain all

of said gates in their article retaining positions and adapted by movement in one direction to successive predetermined positions to release said gates successively and by movement in the opposite direction through said positions to permit said gates to be returned successively to their article retaining positions and maintained therein, separate releasing means associated with each of said locking means and adapted to be actuated to move said locking means in said one direction step by step to said successive positions, a movable member, a separate actuator adjustably mounted on said member adjacent each of said releasing means for movement to and from a position for operative association with said releasing means, a separate selector associated with each actuator and movable to adjust the position of the latter, and means for moving said member to actuate one of said releasing means, and coin controlled means for locking said moving means, means for locking said movable member, and mechanism adapted to be actuated by any selector, when moved to adjust its associated actuator to its operative position, to unlock said movable member and move any other selector and dislodge its associated actuator from its operative position.

GEORGE P. MERGENS.
